UNITED STATES PATENT OFFICE

CHARLES H. KIRBY, OF FLINT, MICHIGAN, ASSIGNOR TO MARVEL CARBURETER COMPANY, OF FLINT, MICHIGAN, A CORPORATION OF ILLINOIS

HEAT CONTROL MECHANISM

Application filed April 3, 1929. Serial No. 352,176.

This invention relates to improved and simplified forms of manifold construction for internal combustion engines wherein it is desirable to provide for the heating of the carbureted mixture and to vary the heating effect under varying conditions of operation.

It is, therefore, an object of this invention to provide improved mechanism for regulating the diversion of exhaust gases into a jacket or heater associated with the intake manifold, and to provide means for operating the mechanism in predetermined but adjustable relationship to the normal carbureter throttle control whereby seasonal and operating conditions may be compensated for.

More specifically, it is an object of this invention to provide an improved heat control adapted to compensate for variations in temperature and operating conditions by providing improved and simplified means for regulating the heat supply in inverse proportion to the throttle opening movement and to vary both the full heat position and the ratio of movement of the heat control relative to the throttle position.

Other and further important objects of this invention will be apparent from the disclosures in the specification and the accompanying drawings.

This invention (in a preferred form) is illustrated in the drawings and hereinafter more fully described.

On the drawings:

Figure 1 is an elevation of one form of manifold construction embodying the features of this invention.

Figure 2 is a section on the line II-II of Figure 1.

Figure 3 is a section on the line III-III of Figure 2.

Figure 4 is a section on the line IV-IV of Figure 3.

Figure 5 is a section on the line V-V of Figure 3.

Figure 6 is a fragmentary end view of the adjustable exhaust valve lever.

Figure 7 is an elevation of a modified embodiment of this invention.

Figure 8 is a section on the line VIII-VIII of Figure 7, with parts in elevation.

Figure 9 is an end fragmentary section on the line IX-IX of Figure 8.

Figure 10 is an end fragmentary section on the line X-X of Figure 8.

As shown on the drawings:

The two embodiments of this invention differ principally in the arrangement of the manifolds to suit different designs of engine cylinder blocks. In Figures 1 to 6, the manifold mountings are more or less conventional as an exhaust manifold 15 is superimposed above an intake manifold 16 both of which have connecting flanges 17 for attachment to individual or siamesed ports in the side of the engine cylinder block (not shown). On the other hand, the exhaust manifold 18 of Figures 7 to 10 is intended to be mounted above upwardly opening ports in the head of an engine block while no intake manifold as such is shown, as a single connection 19 leads to a port in the side of the cylinder block which contains cored distributing passages corresponding to the intake manifold 16 of the first form.

In Figures 1 to 6, the branched or horizontal intake manifold 16 is supplied by a central riser 20 having a jacket 21, this riser having a connection 22 also jacketed as indicated at 23 and in turn connected to a somewhat conventional carbureter 24 having a continuation 25 of the jacket formed around the location of the throttle valve shaft 26. The jackets 21 and 23 are divided into ducts 27 and 28 by partitions 29, while the carburetor jacket 25 forms a connection for the two ducts around the bottom edges of the partitions.

The ducts 27 and 28 extend into a housing 30 formed on the exhaust manifold in alignment with a cylindrical enlargement 31 disposed crosswise in the manifold. The housing is separated from the manifold enlargement by a disc 32 having ports 33 and 34 opening into the exhaust manifold, which ports communicate with the two ducts 27 and 28 which are maintained separate by an upward continuation of the partitions 29. The disc 32 and its partition are carried by a cover member 35 for ease in assembly.

Exhaust gases entering through the port 33 pass down the duct 27 into the jacket on the

carbureter and thence upwardly in the duct 28 and out through the port 34 into the exhaust manifold.

- In order to cause such a flow of exhaust gases, and to control the amount of diversion of gases through the heating jacket, a butterfly valve 36 is mounted on a shaft 37 in the enlargement 31 to practically close the exhaust manifold when the valve is nearly vertical. The enlargement 31 renders the valve fully effective over a considerable range of movement before further rotation thereof opens up the exhaust manifold to decrease the diversion of exhaust gases. This arrangement results in maintaining the full diversion of the exhaust gases during a portion of the movement of the valve before the diversion is reduced by the opening of the exhaust manifold.
20. The valve shaft 37 also carries a disc 38 having cut away portions 39 corresponding to the ports 33 and 34 in the partition 32, which disc cooperates to reduce the port openings at the same time that the valve acts to increase the area of the free passage in the exhaust manifold.

In order to so operate the valve that the maximum heat will be supplied under idling conditions while the heat supply will be cut off under full power operation, the valve shaft is provided with a lever 40 with a link 41 leading to a lever 42 on the carbureter throttle shaft 43. The lever 40 is curved and, as shown, is provided with three notches 44 or points of attachment 44 for the link end 45; the curvature of the lever, in conjunction with the varying radii of the notches 44 serving to vary the initial setting of the exhaust valve for idling conditions with the result that as the throttle is gradually opened the innermost notch for the rod, as shown in Figure 1, gives the maximum heat supply with delayed reduction of diversion, hence, this adjustment may be called the "hot" adjustment for cold weather driving. When the link end 45 is shifted to the center notch the exhaust valve is rotated somewhat towards its open position thus resulting in an earlier reduction in the amount of exhaust gas diversion as the throttle is opened, Figure 3 showing in dotted lines the extent of angular shift of the lever 40 for this change. In Figure 6 the link end is shown as engaged in the outermost notch in which position the exhaust gases are only partly diverted through the heating jacket even when the throttle is at its idling position, while the diversion of exhaust gases is entirely cut off by the disc before the throttle is more than half open, thus giving a materially reduced heating effect suitable for summer driving.

The modified structure shown in Figures 7 to 10, embodies permanently open ports 46 and 47 in the exhaust manifold 18 which ports have duplex ducts 48 and 49 connected

thereto and leading to opposite sides of a partition 50 in a jacket 51 surrounding the intake riser 19, which has a right angle bend in the jacket and is connected to a carbureter 52 beneath the jacket. A throttle valve shaft 53 is mounted in the manifold riser 19 instead of the carbureter and has a link 54 leading to a lever 55 on a rock shaft 56 which in turn has a lever 57 and a link 58 engageable in any of three notches 59 in a curved lever 60 operating a butterfly valve 61 mounted in a cylindrical enlargement 62 in the exhaust manifold 18. The enlargement 62 is provided with oppositely disposed bands 63 adapted to coact with the end of the valve to provide a closed position therefore extending over about 30 degree rotation of the valve to provide an adjustable temperature control such as has been described in connection with the first embodiment of the device of this invention. The rock shaft 56 is provided in this case because of the extreme offset of the exhaust manifold relative to the throttle valve and provides a convenient point of attachment for the normal driver's throttle control.

The foregoing structures are alike in principle of operation with the exception of the disc 32 controlling the exhaust ports in the first described form. In the operation of both forms of the invention this exhaust valve is designed to have an appreciable range of movement which does not affect the full diversion of exhaust gases through the intake manifold jacket when the throttle is near its idling position. When a maximum degree of heating is desired the linkage is so adjusted in each case as to obtain the full movement of the exhaust valve in its closed range during the first part of the opening movement of the throttle, thus delaying the point at which the diversion of exhaust gases begins to be cut down. At the other extreme the exhaust valve is set to begin to open, and thus to cut down on the diversion of exhaust gases, as soon as the throttle begins to open, thus shifting the range of the exhaust valve movement relative to that of the throttle valve.

It will thus be seen that I have provided an improved heat control linked to the throttle control and easily shifted relative thereto to vary the amount of heat at a given throttle opening to provide for different air temperatures and operating conditions.

I am aware that many changes may be made, and numerous details of construction may be varied through a wide range without departing from the principles of this invention, and I, therefore, do not purpose limiting the patent granted hereon, otherwise than necessitated by the prior art.

I claim as my invention:

1. In combination with the intake and exhaust manifolds of an internal combustion

- engine, a valve in said exhaust manifold, a jacket associated with said intake manifold, a pair of ducts connecting said jacket to said exhaust manifold on either side of said valve, 5 a throttle valve for said intake manifold, a curved lever connected to said exhaust valve, said curved lever having a median slot, a lever connected to said throttle valve, and a rod connected to said last named lever at one 10 end and having a variable pivotal connection with said curved lever, in the slot thereof, at its other end, whereby a selective opening of said exhaust valve is obtainable relative to opening of said throttle valve.
- 15 2. In a combination with the intake and exhaust manifolds of an internal combustion engine, a valve in said exhaust manifold, a jacket associated with said intake manifold, a pair of ducts connecting said jacket to said 20 exhaust manifold on either side of said valve, a throttle valve for said intake manifold, means connecting said throttle valve and said exhaust valve to vary the diversion of exhaust gases in predetermined relationship 25 to the throttle movement and to vary the initial position of said exhaust valve relative to said throttle valve, said means comprising a slotted lever connected to said exhaust valve, another lever connected to said throttle 30 valve, and a rod connected to said throttle valve lever at one end, and having a variable pivotal connection with said exhaust valve lever at its other end in the slot of said lever.

In testimony whereof I have hereunto
35 subscribed my name at Santa Monica, Los
Angeles County, California.

CHARLES H. KIRBY.
